UNITED STATES PATENT OFFICE.

WILLIAM CROZIER, OF THE UNITED STATES ARMY.

DISAPPEARING-GUN MOUNTING.

SPECIFICATION forming part of Letters Patent No. 618,252, dated November 1, 1898.

Application filed March 28, 1896. Serial No. 585,276. (No model.)

To all whom it may concern:

Be it known that I, WILLIAM CROZIER, an officer of the army of the United States, stationed at Governor's Island, in the State of New York, have invented a new and useful Improvement in Disappearing-Gun Mountings, (for which I have obtained Letters Patent in Great Britain, No. 19,590, dated September 4, 1896; in France, No. 259,598, dated September 11, 1896; in Belgium, No. 123,475, dated September 11, 1896; in Italy, No. 42,539, dated September 11, 1896; in Austria, No. 47/4,582, dated November 6, 1897, and in Spain, No. 19,661, dated September 19, 1896,) of which the following is a specification sufficient to enable those skilled in the art to make and use the same.

My invention relates to that class of gun-mountings in which the gun is supported movably and counterweighted so as to disappear below the parapet formed within the pit automatically upon its recoil and resume its firing position by the action of the counterweight; and my invention consists in means whereby to permit the gun to be turned to any position in azimuth and in certain other improvements fully set forth hereinafter and illustrated in the accompanying drawings, in which—

Figure 1 is a longitudinal sectional elevation of a disappearing-gun carriage, gun, and adjuncts embodying my improvements. Fig. 2 is a front view with the gun in an elevated position.

The carriage A has side frames 33, connected by cross-pieces to form a rigid structure, and is supported by a turn-table B, which is under the rear portion of the carriage, and in most instances I prefer to make use, in combination with these parts, of a second outer and concentric turn-table L. These turn-tables may be of any suitable construction. As shown, there are annular bed-rails 45 secured to the foundation and annular upper rails 67 connected with the carriage and an intervening annular series of rollers 89, as usual in such structures. The trunnions 10 of the gun C have their bearings in levers, (or a single lever might be used,) the said levers or lever constituting a frame D, having trunnions 12 about midway of its length, which trunnions have their bearings

in two carriers E E, movable upon rails or guides 13 13 of the carriage A. The carriers E may be sliding carriers bearing directly on the rails 13, or they may be provided with wheels or otherwise movable; but preferably the carriage A is provided with a series of friction-rollers 14, arranged so closely together that the carriers E may slide with little friction thereon.

From the lower end of the frame D hangs a counterweight G, or the frame is otherwise suitably counterweighted, so that except by the recoil of the gun or the application of power to positively draw it down toward a loading position the counterweighting means will serve to carry the gun to and maintain it in its firing position.

The guides or supports 13 for the carriers E instead of being horizontal, as heretofore, are inclined downward toward the forward end of the carriage A. This secures an increased resistance to the backward movement of the gun upon recoil and facilitates the forward movement to elevate the gun, thereby reducing the weight of the counterweight G required to reduce recoil and secure the proper quick elevation of the gun to firing position.

With the parts described is combined any suitable restraining device. I have shown a device in the form of hydraulic cylinders x, formed in the carriers E, with stationary pistons 16 upon stationary piston-rods 17, supported by the carriage, these cylinders being provided with a supply of water or other fluid and with circulating-pipes, as is common in this class of appliance, and therefore need not be fully illustrated.

To properly direct the movements of the breech of the gun, I make use of controlling-rods, as heretofore, such rods having bearings at their upper ends for trunnions 18 upon a strap 19, encircling the breech of the gun, and the lower end of each rod being pivoted at y to a slide 20, sliding between guides 21 upon the side frames of the carriage A and movable by means of a rack 22 upon the slide engaging a pinion 23. The pinion 23 is driven or turned through the medium of gears 24 25, the latter upon a shaft having a hand-wheel 26, and a suitable friction-brake—as, for instance, a ring 27—which is surrounded by a strap 28, the ends of which may be brought together

with more or less force by means of any suitable device, as a screw-shaft 29, having reverse threads fitting those in ears at the end of the strap. By this means, after raising 5 the slide 20 to any desired position, it may be secured in place by tightening the friction-brake or other detent. To secure the increased rigidity, the rods 11 may be connected by an intervening brace 30.

To the carriage A, at one side, is secured 15 a ladder-frame J, supporting a platform 31 and hand-rail 32 in suitable position for the officer who sights or controls the firing of the piece, and adjacent to this supporting-platform is a standard 33, arranged in fixed relation to the carriage and upon which the sighting instrument may be attached. At the rear of the carriage is supported the frame K, used 20 for elevating the projectile, and with a suitable annular rack—as, for instance, a rack 35 at the inside of the flange of the lower rail of the turn-table L—engages a pinion 36 on a shaft driven through intermediate gearing from a pinion 37 on a shaft 38, supported by 25 a bracket on the carriage and provided with crank-handles 39. By this means the carriage may be readily turned to any suitable position.

The foundation is provided with an annular 30 well or opening X to receive the counterweight G and permit the gun-carriage to be turned to any suitable position.

Heretofore in apparatus of this character the axis of horizontal rotation has coincided 35 with the axis of the counterweight at the forward end of the mounting, with the result that the rotation of the carriage was limited in each direction from the contact of some part of the gun-mounting with the parapet 40 after revolving the carriage to a limited extent. I overcome this objection in the construction above described by arranging the turn-table in such respect to the carriage and gun and appurtenances that the axis of the turn-table is about midway between the extreme 45 ends of the apparatus when the gun is in load-

ing position, so that it is then possible to rotate the gun in azimuth in a pit or emplacement of the smallest possible diameter, exceeding only by a slight selected extent the 50 total length of the apparatus and permitting the gun to be brought to any desired position in azimuth.

While a second turn-table L is not absolutely essential, it secures a better support 55 for the carriage and for those portions upon opposite sides of the counterweight G which hang between the two turn-tables, and to cover the counterweight well and secure a convenient platform for maneuvering light 60 floor-plates 40 are extended from one turn-table to the other.

A small platform M is attached to the right cylinder of the carrier E for standing upon when using a sight attached to the trunnion 65 10 of the gun C, where it is sometimes placed.

For hauling the gun from the firing to the loading position by hand a rope-tackle 41 is rove through pulleys 42 and 43 on the levers D and side frames 3, the free end of the rope 70 being carried down to any suitable windlass arrangement on the rear ends of the side frames.

Having thus described the precise construction and arrangement of parts shown, what I 75 claim is—

The combination with the carriage, gun, pivoted frame and counterweight of a disappearing gun, of a turn-table arranged beneath the rear portion of the carriage, a concentric 80 outer turn-table, a counterweight between the two turn-tables, and a well for receiving the counterweight arranged between and beneath the turn-tables, substantially as set forth.

In testimony whereof I have signed my 85 name to this specification in the presence of two subscribing witnesses.

WILLIAM CROZIER.
